His Attorney.

UNITED STATES PATENT OFFICE.

JOHN W. NASMITH, OF MANCHESTER, ENGLAND.

COMBING MACHINE.

Application filed March 21, 1923. Serial No. 626,659.

To all whom it may concern:

Be it known that I, JOHN WILLIAM NASMITH, of Heaton-Mersey, Manchester, England, a subject of the King of Great Britain and Ireland, have invented certain new and useful Improvements in Combing Machines, of which the following is a specification.

In the Nasmith combing machine it is usual to weight the front leather covered 10 detaching roller on each end by a simple hook passing down below the rollers, its lower end being formed to receive the usual weight. When it is necessary to remove the roller the hook, provided with a finger 15 hole for the purpose, is easily lifted from the neck of the roller and placed on the adjacent support (T, Fig. 1). The hook and weight hang loose in this position and are frequently knocked off and fall to the floor 20 causing unnecessary stoppage of the machine until they are recovered.

Although the hooks are easily removed it takes an appreciable time to place them properly and securely on the support.

25 The object of the present invention is to do away with all loose parts that may get out of position or fall and to make the removal and replacement of the hook practically instantaneous, thus appreciably diminishing the time the comber must stop when a roller must be removed from any cause.

The invention will now be fully described with reference to the accompanying drawings, which are not to any special scale, and wherein Figure 1 is a vertical section through part of a Nasmith combing machine, sufficient of the machine being shown for purposes of description of the invention. 40 The parts are shown in this figure as in position for applying the pressure to the roller. Figure 2 is a similar section to Figure 1, the pressure being removed; and Figure 3 is a plan of the parts constituting 45 the invention.

Referring to Fig. 1 of the appended drawings, which is a section through part of a Nasmith combing machine, D is the front leather covered detaching roller to 50 which pressure is to be applied at both ends, H is an L-shaped lever or weight hook which transmits the pressure of the spring N to the neck of the roller, one at each end. The bracket B, shown in plan 55 in Fig. 3, is fixed on the top of the bearing of the bottom rollers and is formed

with a fork F to receive the end of the top roller D and a boss to carry the pivot P on which the weight-hook is engaged. The hook H is formed with a slot S, having a 60 depression at E (Fig. 2) at one end. A piece C, adjustable along the framing of the machine R, serves to regulate the tension of the spring N. In Fig. 1 the parts are shown in working position with the 65 pressure on the roller. The pull of the spring N keeps the depression E engaged on the pivot P, which acts as a fulcrum and pressure is transmitted to the rollers. A slight press with the finger in the direction of the arrow A (Fig. 1) suffices to disengage the depression from the pivot at the same time slightly increasing the tension of the spring and as soon as the depression is clear of the pivot the slot S 70 permits the spring N to instantly pull the whole weight hook to the left and transfer the forward end of the hook from the neck of the roller to the support T where it rests securely, there being no loose parts to get 75 displaced or fall, the whole being in stable position as shown in Fig. 2. To replace the pressure on the neck of the roller a push in the direction of the arrow A (Fig. 2) suffices and the spring instantly locks the 80 hook in position.

The apparatus is described and shown as applied to the rollers of a Nasmith combing machine, but it may be applied to other machines.

I claim:—

1. Apparatus for applying pressure to the top rollers of textile machines, said apparatus comprising a lever operating in a fulcrum pin on the machine framing and 25 bodily movable in relation to said fulcrum pin, and tensioning means applied to one extremity of the lever to apply pressure at the other extremity thereof around the fulcrum to the roller, the lever being so 30 arranged that manual pressure applied thereto will move it about its fulcrum and in that position allow the tensioning means to pull the lever bodily away from the roller being weighted, the whole lever moving 105 bodily in relation to its fulcrum pin.

2. In apparatus for applying pressure to the top rollers of textile machines, a lever operating about a fulcrum pin, one extremity of the said lever resting on the neck 110 of a roller to be weighted and the other having tension applied to it, a rest for the

pressure end of the lever, and an L-shaped slot in the lever in one branch of which the fulcrum pin engages, so that movement of the lever about its fulcrum allows the pin to enter the other branch of the L-shaped slot and permits the tensioning means on the one hand to pull the lever bodily from the roller on to the rest for

the pressure end of the lever, and on the other hand to pull the other branch of the L-shaped slot on to the fulcrum and retain it there when the L-shaped lever is pushed off the rest on to the neck of the roller.

In testimony whereof I have affixed my signature.

J. W. NASMITH.
